UNITED STATES PATENT OFFICE.

HERBERT E. VAN DORN, OF CHICAGO, ILLINOIS.

REINFORCED CAR END.

Application filed June 7, 1920. Serial No. 387,000.

To all whom it may concern:

Be it known that I, HERBERT E. VAN DORN, a citizen of the United States, residing at Chicago, county of Cook, State of Illinois, have invented a certain new and useful Improvement in a Reenforced Car End, and declare the following to be a full, clear, and exact description of the same, such as will enable others skilled in the art to which it pertains to make and use the same, reference being had to the accompanying drawings, which form a part of this specification.

In the use of wooden freight car bodies it frequently happens that abnormal pressure on the end of the car body, either internally as from a shifting of the load of the car or externally as from a blow, shock or the like, occurs. This abnormal pressure may not entirely destroy the wooden end of the body but may split it or distort it in such a way as to make it ineffective as a complete closure and yet it may be used to support or help support supplemental metal closures or end plates.

My invention relates to the provision of metal end panels for car bodies located either on the interior face of a wooden car body end or upon the exterior thereof.

In the drawings, Figure 1 is a transverse sectional elevation of a wooden car body;

Fig. 2 is a horizontal section taken on line 2—2 of Fig. 1; and

Fig. 3 is a vertical section illustrating the metal car end engaged to the interior of the wooden end of the car.

In carrying out the invention, A—A' represent respectively the corner posts of one end of a wooden body freight car. B represents the usual car roof engaged to the corner posts, A—A', and the balance of the usual car frame in the usual manner. C—C' are metal end panels. The end panels C are flanged at the edges, c', so that they may be suitably bolted together and bolted to the respective posts A—A' as at c². D, in Fig. 3, represents the ordinary wooden end of this style of car body, the metal panels being bolted to the upper end frame member of the car at c³ and to the lower end frame member or sill at c⁴.

The number of the protecting metal end panels may be varied to suit the constructor. There may be one or, as shown in the drawings herein, two, or more if desired, so long

as they are suitably engaged together; the configuration in cross section may be a corrugated form as shown in the drawings or it may be plain or any other desirable configuration may be given, the essence of the invention resting in the provision of the sheet metal protective panels engaged either to the interior or to the exterior of the wooden ends already in place in the car body.

Reinforcing metal members, E, are provided and engaged to the floor and roof members E', to which the panels C—C' are engaged to strengthen the structure.

I claim:

1. In a wooden body freight car, the combination with the end frame and wooden sheathing on the inside and outside of said frame, of a corrugated metal end panel overlying the inner sheathing and covering the entire area thereof.

2. In a freight car body having wooden inner sheathing at the end, a corrugated sheet metal panel lying against and covering the inner face of said sheathing.

3. In a freight car body having wooden inner sheathing at the end, a corrugated sheet metal panel lying against and covering the inner face of said sheathing, said panel being made in a plurality of sections fastened together.

4. In a freight car body having wooden inner sheathing at the end, a corrugated sheet metal panel lying against and covering the inner face of said sheathing, said panel being made of a plurality of sections detachably connected together.

5. In a freight car body having wooden inner sheathing at the end, a corrugated sheet metal panel lying against and covering the inner face of said sheathing, said panel being made of a plurality of sections detachably bolted together and detachably bolted to the car body.

6. In a freight car body having wooden inner sheathing at the end, a corrugated sheet metal panel lying against and covering the inner face of said sheathing, said panel having inwardly directed flanges at the side and bottom edges, and means for securing said flanges to the adjacent walls of the car body.

In testimony whereof I sign this specification.

HERBERT E. VAN DORN.
